UNITED STATES PATENT OFFICE.

WILLIAM H. DODGE, OF MONTCLAIR, NEW JERSEY.

SHELL FOR CAPS OR CLOSURES FOR BOTTLES, JARS, CANS, AND THE LIKE, AND PROCESS OF MAKING THE SAME.

No. 829,913.

Specification of Letters Patent.

Patented Aug. 28, 1906.

Original application filed October 31, 1905, Serial No. 285,255. Divided and this application filed February 12, 1906. Serial No. 300,800.

To all whom it may concern:

Be it known that I, WILLIAM H. DODGE, a citizen of the United States, residing at Montclair, in the county of Essex and State 5 of New Jersey, have invented certain new and useful Improvements in Shells for Caps or Closures for Bottles, Jars, Cans, and the Like, and Process of Making the Same, of which the following is a specification.

10 This invention relates to shells for caps or closures for bottles, jars, cans, and the like and process for making the same.

The object of the invention is to provide a shell, and method of making the same, for 15 caps or closures for bottles, jars, cans, and the like.

Other objects of the invention will appear more fully hereinafter.

The invention consists, substantially, in the 20 construction, combination, location, arrangement, and mode of operation, all as will be more fully hereinafter set forth, as shown in the accompanying drawings, and finally pointed out in the appended claims.

25 Referring to the accompanying drawings, and to the various views and reference-signs appearing thereon, Figure 1 is a view in plan of a blank plate from which the shell for a cap or closure for bottles, jars, cans, or the like is to be made. Fig. 2 is a plan view of a

30 blank plate, shown in Fig. 1, drawn into eccentric cup shape and having a peripheral shoulder or projection formed therein in the initial stage of production of the shell. Fig.

35 3 is a transverse central section on the line 33, Fig. 2. Fig. 4 is a view similar to Fig. 2, showing the shell at another stage in its manufacture and after the removal from the base or top thereof of a crescent-shaped strip

40 in order to reduce the top or base to circular contour and to partially separate a portion of the flange from such top or base, but leaving the flange peripherally continuous or integral throughout. Fig. 5 is a view similar 45 to Fig. 4, showing the shell after the shoulder or projection has been rolled out or reduced. Fig. 6 is a top plan view of a cap or closure complete. Fig. 7 is a side view or elevation of the same. Fig. 8 is a broken detail view,

50 in side elevation, of a form of integral connecting-web for connecting the separated portion of the flange with the adjacent or un-

separated portion of the flange. Figs. 9 and 55 10 are broken detail views similar to Fig. 8, showing modified forms and shapes of integral connecting-webs. Fig. 11 is a view similar to Fig. 4, showing a modified form of shell wherein the integral connecting-web portion is formed intermediate the ends of the separated portion of the flange. Fig. 12 60 is a broken view in plan of a completed cap or closure embodying the construction shown in Fig. 11. Fig. 13 is a broken view in plan similar to Figs. 4 and 11, showing a modified form wherein an integral connecting-web is 65 formed at each end of the separated portion of the flange. Fig. 14 is a broken view in plan similar to Figs. 6 and 12, showing a complete cap or closure embodying the construction of Fig. 13. Fig. 15 is a broken view in 70 plan similar to Figs. 4, 11, and 13, showing a modified form of shell employing a plurality of integral connecting-webs in the separated portion of the flange. Fig. 16 is a broken view in plan similar to Figs. 6, 12, and 14, 75 showing a completed cap or closure embodying the structure of Fig. 15. Fig. 17 is a view in side elevation, parts in section, showing the application of a completed cap or closure embodying the principles of my invention to a bottle, jar, can, or the like.

The same part is designated by the same reference-sign wherever it occurs throughout the several views.

The subject-matter of the present application is divided out of my pending application, filed October 31, 1905, Serial No. 285,255.

In the manufacture of caps or closures for bottles, jars, cans, and the like it is desirable 90 to produce a device which is not only simple in construction and economical in manufacture, but also which is capable of being readily, easily, and quickly applied to or removed from the mouth of a bottle, jar, can, or the like, while at the same time efficiently sealing the bottle, jar, can, or the like hermetically when applied thereto. In attaining simplicity of structure and economy in manufacture it is desirable to avoid employing a 95 plurality of parts requiring the necessity for assembling such parts by hand, and in attaining efficiency, rapidity, and ease in the application of the cap or closure to or its removal 100

from a bottle, jar, can, or the like it is desirable to provide means whereby the effective inclosing or surrounding diameter of the cap or closure may be readily contractible.

- 5 It is among the special objects of my present invention to provide a shell or blank and a method of producing the same for use in the manufacture of caps or closures wherein these various purposes and results stated are
 10 accomplished, and in carrying out my invention I propose to form the cap or closure from a single piece of material, preferably of sheet metal—such, for instance, as tin—although I do not desire to be limited or restricted in
 15 this regard. In carrying out my invention I produce from a sheet of the selected metal or material a blank plate of sufficient size and of the desired contour from which a shell is produced and which by suitable and proper
 20 manipulation in successive steps the finished cap or closure as a completed article is formed. In Fig. 1 I have shown at A a blank plate oblong in outline and of sufficient area to produce a completed cap or closure of the desired size. Ordinarily, but in this respect I
 25 do not desire to be limited or restricted, the peripheral edge *a b c* forms a semicircle, and similarly the peripheral edge portion *d e f* forms a semicircle, the dotted lines *a c* and *d f*
 30 representing diameters of said semicircles, respectively, said diameters being of sufficient distance apart from each other to leave the lines *d a* and *f c* substantially parallel with each other, thereby forming substantially a rectangular portion intermediate the
 35 longest dimension of the plate and extending transversely thereacross, thus producing, in effect, an oval or oblong shape plate. A plate so produced is next drawn by stamping,
 40 molding, or otherwise into the form of a cup-shape blank or shell, as shown in Figs. 2 and 3, having a top or base portion B and a flange C. By means of a die or other suitable means a peripheral shoulder or offset D is
 45 formed in the edge of the blank or shell extending transversely of the flange C, as clearly indicated in Fig. 2. It is obvious that the plate A may be cut from the sheet of material and drawn into blank cup-shape or
 50 shell form at one operation. Similarly the offset or shoulder D may be formed at the same time. It is obvious, however, that my invention is in no wise to be limited or restricted in these respects.
 55 It will be observed that the top or base B and the flange C are thus formed integrally with each other and from a single piece of material and that the flange C is peripherally continuous throughout.
 60 In order to produce a cap or closure having a continuous and integral encircling or inclosing flange which is contractible in diameter for ready application to or removal from a bottle, can, jar, or the like, I propose in accordance with the principles of my invention
 65

to separate the flange throughout a portion of its length from the top or base portion B. Therefore and in accordance with the principles of my invention and either before or after the blank plate A is drawn into proper cup-shape to form the blank or shell, or at the same time therewith, I remove a strip or portion by cutting, punching, or otherwise from the top or base B, preferably along a line adjacent to the peripheral edge of said top or base, as indicated at E, Figs. 4 and 5, or otherwise sever such base or top along such line and throughout the desired distance to separate a desirable peripheral length of the flange C from the top or base B, leaving, however, and preferably, a portion F of the top or base attached to the separated portion of the flange. In practice I have found that the removal of a crescent-shaped strip, the outline of which is indicated and shown in Figs. 4 and 5, answers my purpose; but I do not desire to be limited or restricted in this respect. In practice the severing-cut commences at one end adjacent the peripheral shoulder or offset D in the particular form of embodiment of my invention shown in Figs. 4 and 5, and by reason of the shoulder or offset D being formed a portion of the top or base B remains attached or connected to the separated portion of the flange at this point of beginning of the severing-cut. In other words, by providing this offset or shoulder the end of the cut does not extend to the peripheral edge of the top or base at this point, as clearly shown in Fig. 4. By reason of this feature of my construction and arrangement in the production and process of making my cap or closure I am enabled to completely cover up the opening made by the severing-cut or the removal of the strip referred to from the top or base when the separated portion of the flange is subsequently contracted in diameter in the application of the completed article to a bottle, jar, can, or the like. At its other end, in the form illustrated in Figs. 4 and 5, the severing-cut extends, as at G, to the periphery of the top or base B, but not through the flange C, thereby leaving an integral connecting web portion H intermediate the separated portion of the flange and the adjacent unseparated portion of such flange.

It will be observed that before the removal of the strip from the top or base, as above referred to, the said top or base is of eccentric shape, and therefore the removal of the strip reduces the top or base to circular contour and leaves the flange of greater circumferential length than the peripheral length of the top or base, and the completed cap is formed from the shell thus constructed, and, as explained herein, by bending or folding the web, thereby contracting the length of the flange and drawing the flange closely around the top or base.

After the separating-cut is made in the

blank or shell, or after the strip is removed from the top or base, as above explained, or, if desired, at the same time therewith, the shoulder or offset D is rolled out or flattened 5 down, as shown in Fig. 5.

In the manner above described I produce a shell for a cap or closure for bottles, jars, cans, or the like made from a single piece of metal and embodying a top or base portion B and 10 a peripheral flange C, which is peripherally continuous or integral throughout and which is integral with the base or top B, but a portion of which flange throughout a desirable length thereof is separated from the top or base B and wherein a portion of the top or base B remains connected with the separated portion of the flange, thereby forming a lip or rim adapted when the separated portion of the flange is contracted to lap past or over 15 the adjacent severed or free edge of the top or base, as clearly indicated in Fig. 17, thereby forming a closure for the opening made by the removal of the strip from the top or base B or the cut made therein to produce 20 the separated portion of the flange, and in 25 Figs. 6 and 17 I have shown in top plan and side elevation, respectively, a completed cap or closure with the separated portion of the flange contracted in diameter and with the 30 lip F thereof overlapping the adjacent edge of the top or base B.

In order to contract the diameter of the flange to effect overlapping of the lip F upon the adjacent edge of the top or base B to produce the completed article, it is necessary to 35 form the integral connecting portion H into a fold or loop. To facilitate the formation of the integral connecting-web portion H into a loop or bend, I preferably cut out or remove 40 a portion of such web so as to reduce the transverse width thereof, and in Figs. 8, 9, and 10 I have shown at H', H², and H³ various forms of the integral connecting-webs referred to. I do not desire, therefore, to be 45 limited or restricted to the exact shape or outline of the integral connecting web. By thus reducing the transverse width of the connecting-web I facilitate the forming of such web into a loop or bend, (indicated at J, Figs. 50 6, 7, and 17.) If desired, a loop or bend thus formed in the connecting-web may be folded or bent or flattened down against the side surface of the flange in order to prevent an undue projection or protruding thereof. It 55 will be observed that by forming the bend or loop in the connecting-web the diameter of the flange is contracted and the separated portion of the flange is drawn into proper relation, with its lip portion F overlapping the 60 edge of the top or base to produce the completed article as a sealing cap or closure.

It will also be observed that the cap or closure constructed and applied as above described may be readily removed from the bottom, can, jar, or the like by simply unbending 65

or unfolding the loop or fold, thereby increasing the diameter of the flange and unloosening the same.

Should it be desired to effect the breakage or rupture of the integral connecting-web in 70 removing the cap or closure from a jar, bottle, can, or the like, one or more scores or grooves (indicated at K K') may be provided at a convenient point in the length of such web, as indicated in Figs. 9 and 10. 75

In Figs. 11 and 12 I have shown a modified form of blank or shell and a cap or closure made therefrom, but embodying the principles of my invention and wherein the integrally-connecting web H⁴ instead of being 80 formed at the end of the cut E' is formed intermediate the ends of such cut, or rather intermediate the ends of the separated portion of the flange. In this instance a shoulder or offset D' is formed on opposite sides of 85 the blank or shell and at each extremity of the cut E', thereby leaving a lip F' connected with the separated portion of the flange on each side of the integral connecting-web H⁴, as clearly shown in Figs. 11 and 12. In this 90 form of device the completed article is produced by forming the web into a fold or loop J' in similar manner to that above described with reference to the construction shown in Figs. 6, 7, and 17, thereby contracting or 95 drawing together the separated portion of the flange, with the lips F' overlapping or lapping past the adjacent edge of the top or base B.

In Figs. 13 and 14 I have shown another modified form of shell and cap or closure produced therefrom embraced within the spirit and scope of my invention and wherein an integral connecting-web H⁵ is formed at each 100 end of the cut or at each end of the separated portion of the flange. In this form the completed cap or closure is produced by bending or folding the webs H⁵, as indicated at J², 105 thereby contracting the diameter of the flange and drawing the separated portion into proper position, with the flange F² thereof overlapping the adjacent edge of the top or base. 110

In Figs. 15 and 16 I have shown another modified form of shell and cap or closure made therefrom embodying the principles of my invention and wherein the separated portion of the flange is provided with a plurality of integral web portions H⁶, each of which is formed into a bend or loop J³ to contract the diameter of the flange and to form the completed article, a lip F³ being formed intermediate each loop H⁶ and respectively adapted to overlap or lap past the edge of the top or base when the separated portion of the flange is contracted in diameter. 115 120

In Fig. 17 I have shown a completed cap or closure applied to a bottle, jar, can, or the like, and in the application of such cap or closure I prefer to employ a sealing-disk 1, which I place within the bottom of the cap or closure and which rests upon the end sur- 130

4
face of the edge of the bottle, jar, can, or the like to which the cap or closure is to be applied, and in order to secure the cap or closure upon the jar, can, bottle, or the like the flange C may be crimped under the bead or shoulder formed at the neck or mouth of the bottle, jar, can, or the like, as indicated at M, and in a well-understood manner.

I do not claim herein the broad idea of a cap or closure for bottles, jars, cans, or the like formed from a single piece of material and having a continuous partially-separated flange provided with a contractible portion, as the same is claimed in my pending application, Serial No. 285,255, filed October 31, 1906, hereinabove referred to.

From the foregoing description it will be observed that the purpose of forming the blank plate A of oblong or oval shape is to reduce the top or base to circular contour and of less peripheral length than the circumferential length of the flange and to enable the separation of the flange to be made for a portion of its length, so as to render said flange contractible in diameter to produce a circular inclosing flange in the completed article, and therefore the degree of oval or oblong will be dependent more or less upon the degree of contractibility desired or upon the extent or area of strip removed from the top or base to effect a separation of the portion of the flange.

From the foregoing description it will be seen that I provide an exceedingly simple and efficient blank or shell and method of producing the same to be formed into a cap or closure for bottles, jars, cans, or the like and wherein all the parts thereof are integral with each other, wherein the flange which encircles the mouth of the bottle, jar, can, or the like is continuous throughout its peripheral length and is contractible in diameter, so as to be formed readily and easily into the completed cap or closure.

As above indicated, it is obvious that many variations and changes in the details of construction, arrangement, and modes of operation would readily occur to persons skilled in the art and still fall within the spirit and scope of my invention. While, therefore, I have shown and described the various forms, embodiments, and modes of operation involving the principles of my invention, I do not desire to be limited or restricted in the broad and generic sense of my invention to the specific details shown and described; but

What I do claim as new and useful and of my own invention, and desire to secure by Letters Patent, is—

1. The method which consists in forming a plate or blank into an eccentric-shaped shell having a base or top and a peripherally-continuous flange, and then removing a strip from the base or top along a line adjacent the periphery thereof, and for a portion of its

peripheral length, to reduce the base or top to circular contour without reducing the circumferential length of the flange and to separate a portion of the flange from the top or base.

2. The method which consists in forming a blank plate into an eccentric-shaped shell having a base or top and an integral peripherally-continuous flange, and then removing a strip from the base or top along a line adjacent the peripheral edge thereof, and for a portion of its peripheral length to reduce the top or base to circular contour and to sever a portion of the length of the flange from the base or top thereby leaving the flange of greater circumferential length than the peripheral length of the top or base.

3. The method which consists in forming a blank plate into an eccentric-shaped shell having a base or top and a peripherally-continuous flange, then removing a strip from the base or top on a line adjacent the peripheral edge thereof for a portion of its length to reduce the base or top to circular contour and to sever the flange from the base or top for a portion of its peripheral length, the line of cut for the removal of such strip being sufficiently removed from the peripheral edge of the base or top to leave a severed portion of the base or top integral with the separated portion of the flange to form a lapping lip and leaving the flange of greater circumferential length than the peripheral length of the top or base.

4. The method which consists in forming a blank plate into an eccentric-shaped shell having a base or top and a flange integral therewith and continuous throughout the length thereof, and then removing a strip from the top or base to reduce the same to circular contour and to separate the flange for a portion of its peripheral length from the base or top, thereby leaving the flange of greater diameter than the diameter of the top or base and finally reducing the width of a portion of the separated part of the flange, whereby said flange is made contractible in diameter.

5. The method which consists in forming a blank plate into a shell oblong in shape and having a base or top and an integral continuous flange, and then removing a strip from the top or base to reduce the same to circular contour and to separate the flange from the base or top for a portion of its peripheral length and leaving the flange of greater circumferential length than the peripheral length of the top or base.

6. The method which consists in forming a blank plate into an oblong shell having a base or top and an integral continuous flange, and then removing a strip from the top or base to reduce the same to circular contour and to separate said flange from the base or top for a portion of the peripheral length of

said flange, thereby leaving the flange of greater diameter than the diameter of the top or base and finally forming a foldable portion in the flange, whereby said flange may be contracted in diameter.

7. The method which consists in forming a plate into an eccentric-shaped shell having a base or top and an integral continuous flange, then forming a shoulder in said shell transversely of the flange, and finally removing a strip from the top or base to reduce the same to circular contour and to separate the flange from the base or top for a portion of the peripheral length of such flange commencing adjacent such shoulder thereby leaving the flange of greater circumferential length than the peripheral length of the top or base.

8. The method which consists in forming a blank plate into an eccentric-shaped shell having a base or top and an integral continuous flange, then forming a shoulder in said shell extending transversely of the flange, and removing a strip from the base or top adjacent the flange and for a portion of the peripheral length of the latter, commencing adjacent said shoulder to reduce the diameter of the top or base without reducing the diameter of the flange and to separate the flange from the top or base for a portion of its length.

9. The method which consists in forming a blank plate into an eccentric-shaped shell having a base or top and an integral continuous flange, then forming a shoulder in said shell extending transversely of the flange, and removing a strip from the base or top adjacent the flange and for a portion of the peripheral length of the latter, commencing adjacent said shoulder, thereby reducing the diameter of the top or base without reducing the diameter of the flange and finally rolling out or reducing said shoulder.

10. The method which consists in forming a blank plate into an eccentric-shaped shell having a base or top and an integral continuous flange, then forming a shoulder in said shell extending transversely of the flange, and removing a strip from the base or top adjacent the flange and for a portion of the peripheral length of the latter, commencing adjacent said shoulder, thereby reducing the diameter of the top or base without reducing the diameter of the flange and finally forming a foldable portion in the separated part of the flange.

11. The method which consists in forming a blank plate into an eccentric-shaped shell having a base or top and an integral continuous flange, then forming a shoulder in said shell extending transversely of the flange, and removing a strip from the base or top adjacent the flange and for a portion of the peripheral length of the latter, commencing adjacent said shoulder, thereby reducing the diameter of the top or base without reducing

the diameter of the flange and finally forming a weakened foldable portion in the separated part of the flange.

12. The method which consists in forming a plate into a shell of oblong shape and having a base and an integral peripherally-continuous flange, and then removing a crescent-shaped strip from the base or top along and adjacent to one of the ends thereof to reduce the top or base to circular contour and to separate the flange from the base or top for a portion of the peripheral length of the flange, thereby leaving the flange of greater circumferential length than the peripheral length of the top or base and finally forming a foldable portion in the separated part of the flange.

13. A shell for forming a cap or closure for bottles, jars, cans or the like, including a top or base and a continuous peripheral flange integral therewith, said shell being longer in diameter across the top or base in one direction than in the other, said flange being separated from the base or top for a portion of its peripheral length.

14. A one-piece shell for forming a cap or closure for bottles, jars, cans or the like, consisting of a top or base and a peripheral continuous flange formed integrally therewith, but separated therefrom for a portion of its peripheral length, said shell being longer in diameter across the top or base in one direction than in the other.

15. A shell for forming a cap or closure for bottles, jars, cans or the like, having a top or base and a peripheral flange formed integrally therewith, said top or base having a slit or opening formed therethrough to separate the flange therefrom for a portion of the length of the latter.

16. A shell for forming a cap or closure for bottles, jars, cans or the like having a top or base and a peripheral continuous flange formed integrally therewith, said top or base having a slit or opening therethrough adjacent its peripheral edge to separate the flange therefrom for a portion of the length of the flange.

17. A shell for forming a cap or closure for bottles, jars, cans or the like, having a top or base and an integral continuous peripheral flange, said top or base having a slit or opening therethrough along and adjacent the periphery thereof to separate the flange therefrom for a portion of the length of the flange, said flange having a foldable portion.

18. A shell for forming a cap or closure for bottles, jars, cans, or the like, having a top or base and an integral continuous flange, said flange being separated from the base or top for a portion of the length of said flange, the separated portion of the flange having a lip or rim to lap upon or over the adjacent edge of the base or top.

19. A shell for forming a cap or closure for bottles, jars, cans or the like, having a top or

base and an integral peripheral continuous flange, said flange being separated from the base or top for a portion of the length of said flange, the separated portion of said flange having a foldable part and a lip or rim.

20. A shell for forming a top or closure for bottles, jars, cans or the like, having a top or base and an integral continuous peripheral flange, said top or base having a substantially crescent-shaped opening formed therethrough adjacent the peripheral edge thereof to separate the flange therefrom for a portion of the length of said flange, the separated portion of the flange having an engaging rim or lip, said flange having a foldable portion.

21. A shell for forming a cap or closure for bottles, jars, cans or the like, having a top or base and a continuous peripheral flange formed integrally therewith, said flange having a shoulder formed in the side thereof, the base or top having a slit or opening formed therein, said slit or opening extending from a point adjacent the shoulder partially around the periphery of the base or top to separate the flange therefrom for a portion of the peripheral length of the latter.

22. A shell for forming a cap or closure for bottles, jars, cans or the like, having a top or base and a continuous peripheral flange formed integrally therewith, said shell having a shoulder formed in the side thereof, the base or top having a slit or opening formed there-

through, beginning near the shoulder and continuing adjacent the peripheral edge of the base or top to separate the flange therefrom for a portion of the circumferential length of the flange, said slit or opening continuing to the flange to form a foldable portion in the separated part of the flange.

23. The method which consists in forming a blank plate of longer dimension in one direction than the other, then drawing said plate into an eccentric-shaped shell having a top or base and an integral continuous peripheral flange, then removing a strip from the top or base along its peripheral edge to separate the flange from the base or top for a portion of the length of the latter and to reduce the base or top to circular contour, leaving a portion of the top or base on the separated portion of the flange to form an engaging lip or rim and leaving the flange of greater circumferential length than the peripheral length of the top or base and finally forming a foldable portion in the separated part of the flange.

In testimony whereof I have signed my name to this specification, in the presence of two subscribing witnesses, on this 5th day of February, A. D. 1906.

WILLIAM H. DODGE.
